UNITED STATES PATENT OFFICE.

ARTHUR ROSENTHAL AND MORRIS G. ROSENTHAL, OF GRAND RAPIDS, MICHIGAN.

SEWING-MACHINE.

1,355,914.

Specification of Letters Patent. Patented Oct. 19, 1920.

Application filed August 27, 1918. Serial No. 251,627.

To all whom it may concern:

Be it known that we, ARTHUR ROSENTHAL and MORRIS G. ROSENTHAL, citizens of the United States, residing at Grand Rapids, 5 county of Kent, State of Michigan, have invented certain new and useful Improvements in Sewing-Machines, of which the following is a specification.

This invention relates to improvements in 10 sewing machines.

Our improvements relate particularly to sewing machines for attaching labels, patches and reinforcements to garments and laundry and the like, and we have illustrated 15 and described our improvements as we have adapted the same for use in attaching marking labels. In this specification and in the claims we use the terms label and label holder as a matter of convenience. It should 20 be understood that we do not use it in a restricted sense but intend to include thereby patches, reinforcements, and any other work for which our improvements may be adapted, and this adaptation is quite general.

25 The main objects of the invention are:

First, to provide an improved machine for the attaching of labels which is of large capacity and convenient and simple to use.

Second, to provide an improved machine 30 having these advantages in which the work is manually manipulated to guide it to the needle.

Third, to provide an improved means for feeding the labels to the label holder.

35 Fourth, to provide an improved label holder.

Fifth, to provide an improved means for cutting the threads.

Further objects, and objects relating to 40 structural details, will definitely appear from the detailed description to follow.

We accomplish the objects of our invention by the devices and means described in the following specification. The invention 45 is clearly defined and pointed out in the claims.

A structure which is a preferred embodiment of our invention is clearly illustrated in the accompanying drawing, forming a 50 part of this specification, in which:

Figure I is a detail perspective of a structure embodying the features of our invention, only such portions of a sewing machine

being illustrated as are deemed necessary to show an adaptation of our improvements. 55

Fig. II is a plan view with the bed and head of the machine omitted.

Fig. II^A is a plan view of the parts shown in Fig. II in another position illustrating the manipulation thereof. 60

Fig. III is a detail longitudinal section on a line corresponding to line 3—3 of Figs. II and V, with the parts in their operative or work engaging position.

Fig. IV is a detail longitudinal section 65 corresponding to Fig. III with the parts raised from the work.

Fig. V is an enlarged detail section on a line corresponding to line 5—5 of Figs. II and III. 70

Fig. VI is a detail plan view of the shoe with the feed member mounted thereon, the feed member being shown in its retracted position, a label being shown on the feed table. 75

Fig. VII is a plan view of the parts shown in Fig. VI with the feed member in its actuated position.

Fig. VIII is a perspective view of the work holder or work engaging member of 80 the presser foot.

Fig. IX is an inverted perspective view of the work holder or work engaging member of the presser foot.

Fig. X is an enlarged detail section on a 85 line corresponding to line 10—10 of Fig. II, showing details of the thread cutting mechanism.

Fig. XI is an enlarged detail section on a line corresponding to line 11—11 of Fig. II, 90 showing details of the thread cutter.

Fig. XII is a detail section corresponding to that of Fig. XI, taken on line 12—12 of Fig. II^A, showing parts of the thread cutter 95 in another position.

Fig. XIII is a perspective view of the thread cutter knife.

Fig. XIV is a plan view of the fixed shear plate of the thread cutter.

Fig. XV is an enlarged detail section 100 through the work holder and shoe on a line corresponding to line 15—15 of Fig. II^A, showing the manner of clamping the labels.

Fig. XVI is an enlarged detail section of the shuttle thread cutter. 105

Fig. XVII is an enlarged detail section

through the head with the face plate thereof removed, showing the means for operating the presser foot bar from the needle bar.

Fig. XVIII is an enlarged front elevation 5 of a portion of the head, showing the adjusting means for regulating the movement of the presser foot bar.

Fig. XIX is a detail plan view of a modified form of guide.

10 Fig. XX is a detail plan view showing still another modification in the form of the guide.

15 In the drawing similar reference characters refer to similar parts throughout the several views, and the sectional views are taken looking in the direction of the little arrows at the ends of the section lines.

20 Referring to the drawing, 1 represents the bed of a sewing machine, 2 the arm and 3 the head carrying the needle bar 4 and the presser foot bar 5. The shuttle mechanism is not shown. The driving means are not illustrated as they form no part of this invention.

25 To actuate the presser foot bar in proper synchronism with the needle bar we provide an actuating lever 7 (see Fig. XVII) pivoted at 8 with one arm disposed to engage the collar 9 on the presser foot bar and the other an actuating pin 10 on the needle bar. To regulate the stroke of the presser foot bar we provide an adjusting cam 11 carried by the set screw 12 (see Fig. XVIII for detail) disposed through a slot 13 in the face plate 14 of the head, the cam being supported by the pin 15 so that it may be adjusted under the collar to constitute an adjustable stop therefor.

40 The presser foot bar is raised to inoperative position by the lever 16. The connections for the lever to the bar are not shown as suitable means are well-known in the art and we use any well known construction.

45 We mount a supporting plate or slide 17 on the bed below the arm 2. This slide is slotted at 18 to engage the post 19 so that the supporting slide is supported for sliding and pivotal movement on the bed. The slide 17 is provided with slotted bearings 20 for the horizontal pivots 21 of the frame 22. At its forward end this frame carries a work holder or carrier 23 having a label opening 24 therein. A thin plate 17' extends beyond the slide 17 to the front of the machine where it constitutes a work supporting plate, the same being suitably perforated under the needle with an aperture corresponding to the particular label or patch to be attached. The frame-like presser foot label holder 25

50 has a rearwardly projecting arm 26 with horizontal pivots 27 thereon (detailed in Figs. VIII and IX) resting in slot-like bearings 28 (Figs. VI and VII). The arm 26 projects rearwardly beyond its pivots 27 and its 65 rear end is engaged by the vertical spring pin

29 arranged through the frame with its upper end engaged by the blade spring 30 secured to the frame at 31 (see Figs. I, II, III and IV). This yieldingly holds the label holder 25 in elevated position. 70

At the front of the opening 24 (see Figs. VI and VII) in the work holder or carrier is a feed table 32 for the labels, shown lying on the feed table at 33,—see Fig. VI. The reciprocating feed member 34 is slidably 75 mounted on the frame so that when in its retracted position, as shown in Fig. VI, a label may be laid in front of it. This feed member is secured in retracted position by means of the catch 35 pivoted at 36. A 80 spring 37 is provided to actuate the feed member and a finger piece or pin 38 projects above the frame so that it may be conveniently retracted manually.

85 The label holder 25 has inclined guides 39 on its front side (detailed in Fig. VIII) so that as the label is advanced by the feed member 34 it will be guided under the label holder. The label holder 25 is preferably provided with teeth 40 and the work holder 90 23 with openings 41 for the teeth (detailed in Fig. XV), so that the label is very firmly clamped to the holder along the edges of its opening 24, the position of the label while stitching being shown in Fig. III. After 95 the stitching is completed the work holder is released and, as the label holder is raised from the work, allows the edges of the label to slip through the label opening 24.

100 The frame 22 is provided with hand pieces 42 at each side which may be grasped for manipulation of the frame. The label holder is clamped upon the label by means of the presser plate 43 which is disposed on and carried by the presser bar 5. This plate 105 43 also constitutes a guide member and a means for raising the frame. To accomplish this the frame is provided with a guide member 44 which, in the embodiment shown in Fig. I, is in the form of a bar carried by 110 an arm 45, so that it overhangs the rear end of the presser plate 43. The presser plate (see Figs. III and IV) is provided with an upwardly projecting pin 46 which travels along the rear side of this bar preventing 115 the forward movement of the frame during its first work stroke. The frame 22, in the embodiment shown in Fig. I, is provided with a flange-like guide member 47 at the sides and front of the presser plate with 120 which the presser plate 43 coacts, thus limiting the rearward and lateral swing of the frame (see plan detailed in Figs. II and II^A).

125 The frame may be completely guided from a guide member substituted for the guide member 44, as in Fig. XIX, in which a star-like guide 48 is provided, the pin 46 of the presser plate coacting with the guide. We particularly show this star-like form of 130

guide as our machine is well adapted for the stitching of stars to a flag, or other irregular labels or patches as may be desired.

In the modification shown in Fig. XX the 5 guide bar 44 is retained and to coat there-with we provide a guide member 49 positioned to guide the pin 46 on the presser plate throughout the full movement of the frame.

10 With the parts thus arranged, the labels are laid on the feed table, as shown in Fig. VI, and the feed member 34 released by releasing catch 35 to project them below the holder by the action of spring 37. The 15 presser foot bar is then lowered by means of its adjusting lever 16 which carries the label holder 25 down upon the label and with it the frame is carried down to bring its work holder 23 upon the work indicated at 50,— 20 see Figs. III and IV. As the stitching progresses the frame is manually manipulated from the handles 42 to guide the work to the needle, so that the label is stitched about its edges.

25 When the stitching is completed the threads are cut, the lower thread being cut by the mechanism shown in Fig. XVI, which consists of a lever 51 having a hand piece 52 projecting above the bed of the machine. The lever engages a knife 53 pivoted at 54, the lever being slotted at 55 to engage the pin 56 on the knife. A fixed shear bar or plate 57 coacts with the knife.

To draw the thread across the shear bar 35 57 we mount a finger 58 in front of the knife so that it engages the thread and draws it against the edge of the shear bar, so that it is easily severed by the knife.

To cut the upper thread we provide a cutter 59 (detailed in Fig. XIII) which is slidably mounted on the frame to coat with a fixed shear bar or plate 60 (detailed in Fig. XIV). This cutter 59 is carried by a slide 61 having an arm 70 projecting through the 45 post 71 pivoted on the post 19 and slotted at 72 to receive the arm 70. The arm 70 is provided with a stop collar 73 adapted to engage the post (see Figs. I, II, II^A, III, IV, X, XI, XII, XIII and XIV).

50 A cutter actuating lever 74 is pivoted on the frame 22 at 75 (see Figs. I, II and II^A). When the frame is in its raised position the actuation of the knife is prevented by the stop lug 76 on slide 61 which engages a hole 55 77 in the presser plate 43,—see Fig. XII. This prevents the knife being actuated while in this position which, if done, would cut off or break the needle.

To hold the thread after it is severed we 60 provide a spring 78,—see Fig. XI, mounted so that the end of the thread after it is severed is drawn under this spring. An adjusting screw 79 is provided for the spring.

When the stitching is completed both 65 threads may be quickly severed and upon

raising the presser foot bar the work holder is released and the frame elevated by means of the presser plate engaging under the guide member 44.

As the frame is pushed rearwardly the 70 stop 73 engages the post 72 limiting the movement of the knife slide and owing to the engagement of the lever 74 therewith the lever is carried rearwardly to the position shown in Fig. II^A. 75

With this arrangement of parts we provide a machine which is of very large capacity and one which is very convenient to operate. The various parts of this machine are operated manually, so far as controlling 80 of the work and the label is concerned. The presser bar lever 16 is thrown to the elevated position and the various parts separated, as indicated in Fig. IV. The work 50 (for instance, a garment to which a laundry label 85 is to be attached) is placed on the plate 17' under the needle. The label feed device 34 is retracted manually and is retained by the catch 35. A label 33 is placed on the feed table 32 and the catch 35 is released by a 90 touch of the finger. The label is then fed forward under the label presser foot. The lever 16 is then dropped and the presser bar forces the label presser foot against the label onto the support 23, clamping it securely 95 and forcing the plate down against the work 50 on the plate 17'. This movement releases all of the locking devices and the operator grasps the handles 42 and feeds the label manually under the needle, when it will be 100 stitched around its edges. The guiding flange 47 and the guiding blocks coöperate to facilitate that manipulation.

When the stitching is completed, the lower thread is cut by manipulating the 105 lever 52 (see Fig. XVI), as already pointed out. The upper thread is cut by manipulating the lever 74. The presser bar lever 16 is then raised and the label is pulled through the plate 23, because it is now stitched to the 110 work 50, and the same may be readily removed as seen in Fig. IV, which shows the parts of my machine in the position that they take after releasing the stitched label and work. 115

The relations of the superposed parts during the stitching operation are clearly seen in Figs. V and XV, where the perforated work holder plate 17' is at the bottom, on which is disposed the work 50, retained by 120 the work holder plate 23, and the label 33 is retained thereon by the label presser foot 25. The machine we have illustrated and described is especially designed by us for the attaching of laundry marking labels, our 125 improvements may, however, be readily adapted for various uses. We have not illustrated or described the various uses as we believe the disclosure made will enable those skilled in the art to which this invention re- 130

lates to embody or adapt the same as may be desired.

Having thus described our invention, what we claim as new and desire to secure by Letters Patent, is:

1. In a sewing machine, the combination with the bed and needle and presser bars, of a post on said bed, a supporting slide slotted to engage said post for sliding and swinging movement, a frame provided with a hand piece at each side pivotally mounted at its rear end on said supporting slide, a work holder at the forward end of said frame having a label opening therein, a frame-like label holder pivotally mounted on said frame to coat with said work holder and clamp a label around the edges of the label opening therein, a spring for yieldingly supporting said label holder in its raised position, a presser plate on said presser bar coacting with said label holder and constituting a guide member, said frame being provided with a flange-like coacting guide member at the front and sides of said plate and with a guide bar overhanging the rear end thereof, said plate having a guide pin coacting with said guide bar, the frame being raised by the presser plate engaging said guide bar when the presser bar is elevated, a label feed table on said frame in front of said label holder, said label holder having inclined label guides on its front edge, a feed member slidably mounted on said frame to deliver labels from said table beneath said label holder, an actuating spring for said feed member, a catch for holding said feed member in its retracted position, a thread cutter comprising a shear plate fixed to said frame, a reciprocating cutter, an actuating slide therefor provided with an arm slidably engaging said post, a stop on said arm, and a cutter actuating lever pivoted on said frame to engage said cutter slide, said cutter slide being provided with a stop engaging said presser plate when the parts are in their initial position.
2. In a sewing machine, the combination with the bed and needle and presser bars, of a post on said bed, a supporting slide slotted to engage said post for sliding and swinging movement, a frame provided with a hand piece at each side pivotally mounted at its rear end on said supporting slide, a work holder at the forward end of said frame having a label opening therein, a frame-like label holder pivotally mounted on said frame to coat with said work holder and clamp a label around the edges of the label opening therein, a spring for yieldingly supporting said label holder in its raised position, a presser plate on said presser bar coacting with said label holder and constituting a guide member, said frame being provided with a flange-like coacting

plate and with a guide bar overhanging the rear end thereof, said plate having a guide pin coacting with said guide bar, the frame being raised by the presser plate engaging said guide bar when the presser bar is elevated, a label feed table on said frame in front of said label holder, said label holder having inclined label guides on its front edge, a feed member slidably mounted on said frame to deliver labels from said table beneath said label holder, an actuating spring for said feed member, and a catch for holding said feed member in its retracted position. 70 75

3. In a sewing machine, the combination with the bed and needle and presser bars, of a post on said bed, a supporting slide slotted to engage said post for sliding and swinging movement, a frame provided with a hand piece at each side pivotally mounted at its rear end on said supporting slide, a work holder at the forward end of said frame having a label opening therein, a frame-like label holder pivotally mounted on said frame to coat with said work holder and clamp a label around the edges of the label opening therein, a spring for yieldingly supporting said label holder in its raised position, a presser plate on said presser bar coacting with said label holder and constituting a guide member, said frame being provided with a flange-like coacting guide member at the front and sides of said plate and with a guide bar overhanging the rear end thereof, said plate having a guide pin coacting with said guide bar, the frame being raised by the presser plate engaging said guide bar when the presser bar is elevated, a thread cutter comprising a shear plate fixed to said frame, a reciprocating cutter, an actuating slide therefor provided with an arm slidably engaging said post, a stop on said arm, and a cutter actuating lever pivoted on said frame to engage said cutter slide, said cutter slide being provided with a stop engaging said presser plate when the parts are in their initial position. 90 95 100

4. In a sewing machine, the combination with the bed and needle and presser bars, of a post on said bed, a supporting slide slotted to engage said post for sliding and swinging movement, a frame provided with a hand piece at each side pivotally mounted at its rear end on said supporting slide, a work holder at the forward end of said frame having a label opening therein, a frame-like label holder pivotally mounted on said frame to coat with said work holder and clamp a label around the edges of the label opening therein, a spring for yieldingly supporting said label holder in its raised position, and a presser plate on said presser bar coacting with said label holder and constituting a guide member, said frame being provided with a flange-like co- 115 120 125 130

5 acting guide member at the front and sides of said plate and with a guide bar overhanging the rear end thereof, said plate having a guide pin coacting with said guide bar, the frame being raised by the presser plate engaging said guide bar when the presser bar is elevated.

- 10 5. In a sewing machine, the combination with the bed and needle and presser bars, of a post on said bed, a supporting slide slotted to engage said post for sliding and swinging movement, a frame provided with a hand piece at each side pivotally mounted at its rear end on said supporting slide, a 15 work holder at the forward end of said frame having a label opening therein, a frame-like label holder pivotally mounted on said frame to coact with said work holder and clamp a label around the edges 20 of the label opening therein, said label holder being provided with teeth and said work holder with openings therefor, a spring for yieldingly supporting said label holder in its raised position, and a presser 25 plate on said presser bar coacting with said label holder and constituting a guide member, said frame being provided with a flange-like coacting guide member at the front and sides of said plate and with a 30 guide bar overhanging the rear end thereof, said plate having a guide pin coacting with said guide bar, the frame being raised by the presser plate engaging said guide bar when the presser bar is elevated.
- 35 6. In a sewing machine, the combination with the bed and needle and presser bars, of a frame adjustably mounted on the bed for manual manipulation, a work holder on said frame having a label opening therein, a 40 frame-like label holder pivotally mounted on said frame to coact with said work holder and clamp a label around the edges of said label opening therein, means for yieldingly supporting said label holder in its raised 45 position, a presser plate on said presser bar coacting with said label holder and constituting a guide member, said frame being provided with a flange-like coacting guide member at the front and sides of said plate 50 of said plate and with a guide bar overhanging said plate, said plate having a guide pin coacting with said guide bar, the frame being raised by said presser plate engaging said guide bar when the presser bar is elevated, a thread cutter comprising a cutter slide mounted on said frame and provided with an arm, a post on said bed with which said arm is slidably engaged, a stop on said arm coacting with said 55 post, and a cutter actuating lever pivotally mounted on said frame, said cutter slide being provided with a stop lug engaging said plate when the parts are in their initial position.
- 60 7. In a sewing machine, the combination 65

with the bed and needle and presser bars, of a frame adjustably mounted on the bed for manual manipulation, a work holder on said frame having a label opening therein, a frame-like label holder pivotally mounted on said frame to coact with said work holder and clamp a label around the edges of said label opening therein, means for yieldingly supporting said label holder in its raised position, and a presser plate on said presser bar coacting with said label holder and constituting a guide member, said frame being provided with a flange-like coacting guide member at the front and sides of said plate and with a guide bar overhanging said plate, said plate having a guide pin coacting with said guide bar, the frame being raised by said presser plate engaging said guide bar when the presser bar is elevated.

70 8. In a sewing machine, the combination with the bed and needle and presser bars, of a frame adjustably mounted on the bed for manual manipulation, a work holder on said frame having a label opening therein, a frame-like label holder pivotally mounted on said frame to coact with said work holder and clamp a label around the edges of said label opening therein, means for yieldingly supporting said label holder in its raised position, a presser plate on said presser bar coacting with said label holder and constituting a guide member, said frame being provided with a flange-like coacting guide member at the front and sides of said plate 80 and with a guide bar overhanging said plate, said plate having a guide pin coacting with said guide bar, the frame being raised by said presser plate engaging said guide bar when the presser bar is elevated.

85 9. In a sewing machine, the combination with the bed and needle and presser bars, of a frame adjustably mounted on the bed for manual manipulation, a work holder on said frame having a label opening therein, a frame-like label holder pivotally mounted on said frame to coact with said work holder and clamp a label around the edges of said label opening therein, means for yieldingly supporting said label holder in its raised 90 position, a presser plate on said presser bar coacting with said label holder and constituting a guide member, said frame being provided with a flange-like coacting guide member at the front and sides of said plate 95 and with a guide bar overhanging said plate, said plate having a guide pin coacting with said guide bar, the frame being raised by said presser plate engaging said guide bar when the presser bar is elevated, a label feed table on said frame, said label holder having inclined label guides on its edge facing said table, and a reciprocating feed member mounted on said frame to deliver labels from said table to said label holder.

100 10. In a sewing machine, the combination with the bed and needle and presser bars, of a frame adjustably mounted on the bed for manual manipulation, a work holder on said frame having a label opening therein, a frame-like label holder pivotally mounted on said frame to coact with said work holder and clamp a label around the edges of said label opening therein, said label holder being provided with teeth and said work holder with openings therefor, means for yieldingly supporting said label holder in its raised position, a presser plate on said presser bar coacting with said label holder and constituting a guide member, said frame being provided with a flange-like coacting 110 guide member at the front and sides of said plate and with a guide bar overhanging said plate, said plate having a guide pin coacting with said guide bar, the frame being raised by said presser plate engaging said guide bar when the presser bar is elevated.

115 11. In a sewing machine, the combination with the bed and needle and presser bars, of a frame adjustably mounted on the bed for manual manipulation, a work holder on said frame having a label opening therein, a frame-like label holder pivotally mounted on said frame to coact with said work holder and clamp a label around the edges of said label opening therein, said label holder being provided with teeth and said work holder with openings therefor, means for yieldingly supporting said label holder in its raised position, a presser plate on said presser bar coacting with said label holder and constituting a guide member, said frame being provided with a flange-like coacting 120 guide member at the front and sides of said plate and with a guide bar overhanging said plate, said plate having a guide pin coacting with said guide bar, the frame being raised by said presser plate engaging said guide 125 bar when the presser bar is elevated.

130 12. In a sewing machine, the combination

- bar when the presser bar is elevated, a label feed table on said frame, said label holder having inclined label guides on its edge facing said table, and a reciprocating feed member mounted on said frame to deliver labels from said table to said label holder.
10. In a sewing machine, the combination with the bed and needle and presser bars, of a frame mounted for horizontal sliding and pivotal and vertical pivotal movement, a work holder on said frame having a label opening therein, a label holder pivotally mounted on said frame to coact with said work holder and clamp a label around the edges of the label opening therein, means for raising said label holder, a presser plate on said presser bar coacting with said label holder and constituting a guide member, said frame being provided with a flange-like coacting guide member and with a guide bar overhanging said presser plate and coacting therewith, a thread cutter comprising a shear plate fixed to said frame, a reciprocating cutter, an actuating slide therefor, and
- 15 20 25 30 35 40 45 50 55 60 65 70 75 80 85 90 95 100 105 110 115 120 125 130
- a cutter actuating lever pivoted on said frame to engage said cutter slide, said cutter slide being provided with a stop engaging said presser plate when the parts are in their initial position.
11. In a sewing machine, the combination with the bed and needle and presser bars, of a frame mounted for horizontal sliding and pivotal and vertical pivotal movement, a work holder on said frame having a label opening therein, a label holder pivotally mounted on said frame to coact with said work holder and clamp a label around the edges of the label opening therein, means for raising said label holder, and a presser plate on said presser bar coacting with said label holder and constituting a guide member, said frame being provided with a flange-like coacting guide member and with a guide bar overhanging said presser plate and coacting therewith.
12. In a sewing machine, the combination with the bed and needle and presser bars, of a frame mounted for horizontal sliding and pivotal and vertical pivotal movement, a work holder on said frame having a label opening therein, a label holder pivotally mounted on said frame to coact with said work holder and clamp a label around the edges of the label opening therein, means for raising said label holder, a presser plate on said presser bar coacting with said label holder and constituting a guide member, said frame being provided with a flange-like coacting guide member and with a guide bar overhanging said presser plate and coacting therewith, a label feed table on said frame, a reciprocating feed member mounted on said frame to deliver labels from said table to said label holder, an actuating spring for said feed member, and a catch
- for holding said feed member in its retracted position.
13. In a sewing machine, the combination with the bed and needle and presser bars, of a post on said bed, a supporting slide slotted to engage said post for sliding and swinging movement, a frame provided with a hand piece at each side pivotally mounted at its rear end on said supporting slide, a work holder at the forward end of said frame, a label holder on said frame, a presser plate on said presser bar coacting with said label holder, a thread cutter comprising a shear plate fixed to said frame, a reciprocating cutter, an actuating slide therefor provided with an arm slidably engaging said post, a stop on said arm, and a cutter actuating lever pivoted on said frame to engage said cutter slide, said cutter slide being provided with a stop engaging said presser plate when the parts are in their initial position.
14. In a sewing machine, the combination with the bed, of a post on said bed, a supporting slide slotted to engage said post for sliding and swinging movement, a frame provided with a hand piece at each side pivotally mounted at its rear end on said supporting slide, a work holder at the forward end of said frame, a label holder on said frame, a thread cutter comprising a shear plate fixed to said frame, a reciprocating cutter, an actuating slide therefor provided with an arm slidably engaging said post, a stop on said arm, and a cutter actuating lever pivoted on said frame to engage said cutter slide.
15. In a sewing machine, the combination with the bed and needle and presser bars, of an adjustable frame, a work holder, a label holder on said frame, a presser plate on said presser bar coacting with said label holder, a thread cutter comprising a shear plate fixed to said frame, a reciprocating cutter, an actuating slide therefor, coacting stop means on said bed and slide, and a cutter actuating lever pivoted on said frame to engage said cutter slide, said cutter slide being provided with a stop lug engaging said presser plate when the parts are in their initial position.
16. In a sewing machine, the combination with the bed, of an adjustable frame, a work holder, a label holder on said frame, a thread cutter comprising a shear plate fixed to said frame, a reciprocating cutter, an actuating slide therefor, coacting stop means on said bed and slide, and a cutter actuating lever pivoted on said frame to engage said cutter slide.
17. In a sewing machine, the combination with the bed and needle and presser bars, of a frame adjustably mounted on said bed for manual manipulation, a work holder on said frame, a label holder on said frame coacting with said shoe to clamp a label, a presser

plate on said presser bar coacting with said label holder, means for guiding the movement of said frame, a label feed table on said frame, and a reciprocating feed member mounted on said frame to deliver labels from said table to said label holder.

18. In a sewing machine, the combination with the bed, of a frame adjustably mounted on said bed for manual manipulation, a work holder on said frame, a label holder on said frame, means for guiding the movement of said frame, a label feed table on said frame, and a reciprocating feed member mounted on said frame to deliver labels from said table to said label holder.

19. In a sewing machine, the combination with the bed, of a frame adjustably mounted on said bed for manual manipulation, a work holder on said frame, a label holder on said frame, means for guiding the movement of said frame, a label feed table on said frame, said label holder having inclined label guides on its edge facing said table, and a reciprocating feed member mounted on said frame to deliver labels from said table to said label holder.

20. In a sewing machine, the combination with the bed and needle and presser bars, of a frame adjustably mounted on the bed for manual manipulation, a work holder on said frame, a label holder, a presser plate on said presser bar coacting with said label holder and constituting a guide member, said frame having a coacting guide member, whereby the frame is guided in its movement, a label feed member mounted on said frame to deliver to said label holder, a thread cutter comprising a cutter slide mounted on said frame, coacting stop members on said cutter and bed, and a cutter actuating lever pivotally mounted on said frame, said cutter slide being provided with a stop engaging said plate when the parts are in their initial position.

21. In a sewing machine, the combination with the bed and needle and presser bars, of a frame adjustably mounted on the bed for manual manipulation, a work holder on said frame, a label holder, a presser plate on said presser bar coacting with said label holder and constituting a guide member, said frame having a coacting guide member, whereby the frame is guided in its movement, and a label feed member mounted on said frame to deliver to said label holder.

22. In a sewing machine, the combination with the bed and needle and presser bar, of an adjustable frame, a work holder on said frame having a label opening therein, a frame-like label holder pivotally mounted on said frame to coact with said shoe and clamp a label around the edges of the label opening therein, and a presser plate on said presser bar coacting with said label holder and constituting a guide member, said

frame being provided with a flange-like coacting guide member and with a guide bar overhanging said presser plate and coacting therewith.

23. In a sewing machine, the combination with the bed and needle and presser bars, of an adjustable frame, a work holder on said frame having a label opening therein, a frame-like label holder pivotally mounted on said frame to coact with said work holder and clamp a label around the edges of the label opening therein, and a presser plate on said presser bar coacting with said label holder and constituting a guide member, said frame being provided with a guide bar overhanging said presser plate and coacting therewith.

24. In a sewing machine, the combination with a presser bar, of an adjustable frame, a work holder on said frame, a label holder on said frame, and a presser plate on said presser bar coacting with said label holder and constituting a guide member, said frame being provided with a flange-like coacting guide member and with a guide bar overhanging said presser plate and coacting therewith.

25. In a sewing machine, the combination with a presser bar, of an adjustable frame, a work holder on said frame, a label holder on said frame, and a presser plate on said presser bar coacting with said label holder and constituting a guide member, said frame being provided with a guide bar overhanging said presser plate and coacting therewith.

26. In a sewing machine, the combination with the bed and needle and presser bars, of a frame adjustably mounted on the bed for manual manipulation, a work holder on said frame, a frame-like label holder mounted on said frame coacting with said work holder to clamp a label around its edges, said label holder being provided with teeth and said shoe with openings therefor, and a presser plate on said presser bar coacting with said label holder and constituting a guide member, said frame having a coacting guide member, whereby the frame is guided in its movement.

27. In a sewing machine, the combination with the bed and needle and presser bars, of a frame adjustably mounted on the bed for manual manipulation, a work holder on said frame, a label holder mounted on said frame, and a presser plate on said presser bar coacting with said label holder and constituting a guide member, said frame having a coacting guide member, whereby the frame is guided in its movement.

28. In a sewing machine, the combination with the bed and needle and presser bars, of a post on said bed, a supporting slide slotted to engage said post for sliding and swinging movement, a frame provided with a

- hand piece at each side pivotally mounted at its rear end on said supporting slide, a work support plate secured to the under side of said slide and extending to the front of said frame with an opening therein corresponding to a label or patch to be attached, a work holder at the forward end of said frame having a label opening therein, a frame-like label holder pivotally mounted 5 on said frame to coact with said work holder and clamp a label around the edges of the label opening therein, a spring for yieldingly supporting said label holder in its raised position, and a presser plate on 10 said presser bar coacting with said label holder and constituting a guide member,

said frame being provided with a flange-like coacting guide member at the front and sides of said plate and with a guide bar overhanging the rear end thereof, said plate having 20 a guide pin coacting with said guide bar, the frame being raised by the presser plate engaging said guide bar when the presser bar is elevated.

In witness whereof, we have hereunto set 25 our hands and seals in the presence of two witnesses.

ARTHUR ROSENTHAL. [L. S.]
MORRIS G. ROSENTHAL. [L. S.]
